UNITED STATES PATENT OFFICE.

GEORGE WACKER, OF NEW YORK, N. Y., ASSIGNOR OF THIRTY-FIVE ONE-HUNDREDTHS TO FRANK H. LAUTEN AND ELLISON SAUNDERS, BOTH OF SAME PLACE.

ICE-MAKING MACHINE.

SPECIFICATION forming part of Letters Patent No. 249,211, dated November 8, 1881.
Application filed May 25, 1881. (No model.)

To all whom it may concern:

Be it known that I, GEORGE WACKER, of the city, county, and State of New York, have invented a new and Improved Ice-Making Machine or Cold-Air Apparatus, worked by compressed air, of which the following is a specification.

My invention relates to improvements in ice or cold-air making machines where compressed air, and no chemicals, is used for the production of ice.

The object of the improvements is to prevent parts of the machine from getting overheated; to use less power; to prevent the forming of icicles in the tubing, piping, valves, and cylinders created by the moisture in the air used in the process of making ice or cold air, and to automatically regulate the degree of compression and expansion in the respective cylinders.

20 The invention consists, first, of a cylinder to compress and heat the air; secondly, of two tanks to contain glycerine or other material of like properties, to fill the air-compressing cylinder alternately at each stroke of the piston with glycerine or other like material; thirdly, of one suction and one compression valve for each of the above glycerine-tanks, to admit air for compression and to discharge it into the cooling tubes; fourthly, of an adjustable faucet to admit the glycerine; fifthly, of a funnel where the glycerine or other like material is poured into the machine; sixthly, of an expansion-cylinder with valves to regulate the power for the working of the machine, to expand and there- 35 by cool the air, and to discharge into the freezing-tank; seventhly, of an outward and an inward tank for the reception of the cold air coming from the expansion-cylinder and reservoir for the smaller tin tanks, wherein the water to 40 be frozen is located; and, lastly, of tubing, piping, &c., necessary for the transmission and connection of the compressed and expanded air through the different parts of the machine, all of which will be fully described in connection 45 with the accompanying drawings.

In the accompanying drawings, Figure 1 is an elevation of my improved ice-machine. Fig. 2 is a longitudinal section of the expansion-cyl-

inder, showing the valves of the same and how they are worked by the piston.

Referring to the drawings, A is a compression air-cylinder, which inner part stands in connection, by openings in the heads of the cylinder, with tanks D and E, which latter hold a volume of fully the capacity of the cylinder each. Tanks D and E have on their upper end each a suction-valve, n and n', and a compression-valve, m and m'. The compression-valves m and m' are connected with a pipe, r, which lies higher than valves m and m'. Pipe r leads 50 into cooler C. From cooler C leads a pipe, s, to expansion-cylinder B, where it is closed by spring-valves z z', Fig. 2, alternately. From expansion-cylinder B leads a pipe, t, which is alternately closed by the slide-valves x and x', 55 to tank F, which incloses freezing-tank G. The pistons a and b of cylinders A and B, Fig. 1, are connected together by their piston-rods, both being firmly bolted to frame L, so that if one moves the other moves also. Shaft K' has 60 its bearings in box T, on the outside of which power is attached to move the same.

The operation of the machine is as follows: Pure glycerine (or other like material) is poured into funnel u, Fig. 1, which transmits it to 65 outer tank F, from where it flows through the opened faucet o to suction-valves n and n'. Shaft K is now slowly rotated until glycerine-tanks D and E and compression-cylinder A are 70 filled with glycerine. Then faucet o is almost 75 closed, so that the glycerine can soak through only drop by drop. At this time tank F must hold so much glycerine that the opening of faucet o is covered by it. As the pistons a and b are moved, a presses the glycerine contained 80 in cylinder A into tank D, after which it flows, after filling valve-box m, into pipe r, and from there to the pipes of cooler C. At the same 85 time, and through the same move of piston a, glycerine is sucked into cylinder A from tank E, while tank E at the same time is sucked full of air, which comes from tank F through pipe P and suction-valve n'. As the volume 90 of cylinder A is equal to the volume of tank E, only glycerine and no air can enter into cylinder A. When the piston a moves back again 95

the glycerine contained in cylinder A is forced back into tank E, where the surface of the glycerine acts as a real piston and presses the air from tank E through valve m' to pipe r , 5 and from there to cooler C, at the same time filling tank E and valve-boxes m' and n' with glycerine again, and air enters into tank D by pipe P and valve n , and also a little glycerine through faucet o , and so at each rotation of 10 the crank K the same operation is repeated.

It is obvious that by the above proceedings cylinder A is always filled with glycerine; also are suction-valves n and n' and compression-valves m and m' always covered with the 15 same, as such is always from faucet o induced drop by drop into suction-valves n and n' . This surplus can only flow off through pipe r after covering compression-valves m and m' , thereby keeping the valves perfectly tight, also 20 the piston and stuffing-box of the cylinder A, and, filling every nook and corner of the latter completely, it prevents the existence of the least vacuum or dead-space in the cylinder. The surplus of glycerine admitted through ad- 25 justable faucet o goes with the compressed air through cooler C, pipe s , and expansion-cylinder B, where it also acts as a lubricator for valves and pistons, and from there it oozes through pipe t into tank F again, from where 30 it commences its course of circulation anew. By the circulation of the glycerine through the whole machine, as shown above, the glycerine furthermore acts as an agent to absorb the moisture out of the air used in making the ice.

35 Box T incloses the whole machine, and water is led through the former to cool the compressed air and the whole machine in general. From cooler C the compressed air goes through pipe s to expansion-cylinder B. This cylinder, Fig. 2, has the same diameter as the compression-cylinder A, but is longer than the former. As piston b has the same stroke as piston a , it follows that piston b can only come within a certain distance to the heads of cylinder B. As shown in Fig. 2, the compressed air 45 enters through pipe s and the valves z and z' into expansion-cylinder B, and after its expansion makes its exit through sliding valves x and x' . Valves z and z' are closed by springs, and 50 the compressed air that presses on them moves the piston b toward valve x . The latter closes near the end of the stroke by adjustable stoppers g and g' ; but as sliding valve x' is firmly connected with sliding valve x , it at the same 55 moment opens the latter. After valve x' is closed the rest of the stroke of piston b comes in contact yet with the inside end of valve z' and opens the same, and while the piston is 60 in contact with z' keeps it open, during which 65 time the compressed air forces itself into the space between piston and head of expansion-cylinder B until the piston loses contact with valve z' , when, of course, the latter closes instantly. Now, the admitted compressed air presses the piston b with as much force as had been used to compress the same, which requires

thereby less power to work the machine. At the move of the piston b toward valve x the air expands and its temperature lowers at once as many degrees as have been added to it by 70 compression. When arrived at valve x the same is closed, x' opened, and z opened and closed in the same manner as described above. The expanded air of low temperature is moved by the piston b out of cylinder B through pipe 75 t , Fig. 1, into tank F and G, where it freezes the water in smaller tin tanks hung into tank G. From tank F the air is sucked through pipe 80 P and suction-valves n and n' into tanks D and E again, and the same procedure 85 commences again its circulation, as heretofore described.

It is obvious that through the size of the space between piston and cylinder-head of expansion-cylinder B the exact degree of expansion, as well as the degree of compression, is given; then, as soon as the air is so much compressed that the volume of air of the compression-cylinder is equal to the amount of compressed air between the head and piston of expansion-cylinder B, the normal pressure is 90 reached, which, it is obvious, remains from this out constantly the same, as the expansion-cylinder emits exactly as much air as the compression-cylinder presses in between the head 95 and piston of cylinder B. By this relative method all meters, &c., are obviated, and in this manner it can in advance be concluded with how much pressure the ice-machine is 100 wanted to work.

This apparatus, as will be readily understood, furnishes an efficient ice-making machine, whereof every working part is excellently lubricated, the moisture absorbed from the used air, and all valves kept perfectly airtight by the glycerine, thereby lessening the power to be applied, and the latter regulated by the proportionate construction of the cylinders, as heretofore described.

Having thus described my invention, I claim 110 as new and desire to secure by Letters Patent—

1. As an improvement in ice-making machines, the combination, with compression-cylinder A, of the glycerine-tank D, connecting in 115 the upper end, and glycerine-tank E, connecting in the lower end of compression-cylinder A, substantially as herein set forth and described.

2. In an ice-making machine, the combination, with cylinder A and piston a , of the suction-valves n and n' , the compression-valves m and m' , and the glycerine-tanks D and E, substantially as herein set forth and described.

3. In an ice-making machine, the combination of pipe P with faucet o and suction-valves n and n' , substantially as herein set forth and described.

4. In an ice-making machine, the combination, with tank F, of the faucet o , substantially as herein set forth and described.

5. In an ice-making machine, the combina-

tion of the sliding valves x and x' with the connecting-bar y , substantially as herein set forth and described.

5. In an ice-making machine, the combination of the adjustable stoppers g g' of piston b with the sliding valves x and x' , substantially as herein set forth and described.

6. In an ice-making machine, the combination of the sliding valves x and x' with the connecting-bar y , substantially as herein set forth and described.

7. In an ice-making machine, the combination of expansion-cylinder B and piston b with sliding valves x and x' and spring-valves z z' and z'' .

GEORGE WACKER.
